STRIP-FEEDING DEVICE.

1,023,165.

Specification of Letters Patent.

Patented Apr. 16, 1912.

Application filed March 22, 1910. Serial No. 550,831.

To all whom it may concern:

Be it known that I, OSCAR OEHRING, a subject of the Emperor of Germany, residing at Berlin, Germany, have invented new 5 and useful Improvements in Strip-Feeding Devices, of which the following is a specification.

This invention relates to a device designed more particularly as an attachment to a self- 10 printing mechanism for printing tickets or the like, and if desired forming perforations or indentations between said tickets, on a continuous web of paper for the purpose of being vended by a coin operated mechanism, 15 although it may be used on machines of other kinds and also when printed strips, wound on a roll, are withdrawn manually therefrom.

The object of this invention is to provide 20 a simple device for regulating the tension of a strip of paper wound into a roll which may be blank on one or both sides for the purpose of printing thereon, either continuously or intermittently a series of impressions to form a continuous ticket strip, or 25 said strip may contain a series of printed subject-matter representing tickets or the like to be torn from said strip when issued.

When a blank strip in roll form is fed 30 to a so-called self-printing machine, wherein the ticket impressions are printed on a strip as they are demanded, the mechanism for feeding the strips to the printing form is operated only when a ticket is demanded 35 and the operation of feeding causes a strip to be delivered intermittently or by jerks through the sudden starting of the feeding devices. This jerky feeding owing to the inertia of the roll which at this time is stationary, is liable to tear the strip and interrupt the operation of the mechanism to which the printing device is connected; for the same reason when a ticket strip is wound in a roll for convenience and expediency in 45 handling the same, the inertia of the roll often causes the strip to tear when the latter is drawn therefrom as the tickets are disposed of. These and other defects are overcome by the improved tension device 50 forming the principal object of the present invention and illustrated in the accompanying drawings, which show the device attached to the self-printing mechanism that may or may not form a part of a vending machine.

In the drawings, *a* is a blank strip, usually of paper, wound on a roll *b* rotatably mounted on a shaft *c* carried by one or more supports *f* rising from the frame of a self-printing machine *n*. The strip *a* passes 60 from the roll *b* to and through a guide *m* on said printing machine and fed thereto either continuously or intermittently by means of a feeding device *o*.

Loosely mounted on the shaft *c* at one end 65 of the roll *b*, or in some other suitable position, is a rocking arm *d* carrying at its lower end a small guide roller *h* over which the strip *a* is carried from the strip roll *a'* to the printing and perforating mechanism, 70 should the latter attachment be desired to weaken sections of the strip. The roller *h* turns on a pin or one leg of a loop *h'* attached to the rocking arm *d*, said pin or loop projecting into a curved slot *g*, concentric with the axis of the shaft *c* in the support *f* on which said shaft is mounted.

Surrounding the shaft *c* and attached to any fixed point is a spring *e*, the opposite 75 end of which is fastened to the swinging arm *d*, and by its tension tends to hold said arm in the position indicated in full lines on the drawing, thereby forming a loop in the strip *a* by means of the roll *h* thereon which draws from the strip roller *a'* a 80 length of the strip *a* equal to or slightly in excess of the amount necessary for a ticket.

When the printing mechanism *n* is set in operation the feed roll *o* thereof begins to 85 rotate and as it bears against the strip *a* the latter is drawn downwardly through the guide *m* to the printing form, not shown. This movement of the strip *a* tends to rotate the strip roll *a'*, but as the resistance of the spring *e* is less than the inertia of the 90 strip roll *a'* the arm *d* is caused to swing on the shaft *c* to the position indicated by dotted lines, at which point a sufficient amount of the strip loop has been fed to the printing machine to produce a ticket. 95 After the ticket has been printed, the feed mechanism *o* comes to rest and the tension being removed from the strip *a* the spring *e* overcomes the inertia of the roll and returns the swinging arm *d* to its initial position 100 drawing from the roll by this movement a sufficient amount of the strip to form another ticket. It will thus be seen that the strip is not subjected to sudden strains or jerks to overcome the inertia and withdraw 105 110

sufficient material for a ticket from the roll a' when the printing feed is put in operation because the necessary length of material to form a ticket is contained within the loop 5 as previously stated. The strip roll therefore will not be rotated by the feed mechanism of the printing machine, but as soon as the latter comes to rest the tension of the spring e acting through the arm d and roller 10 h unrolls enough paper to form the next ticket to be printed.

The roll a' may be a ticket strip roll instead of a roll of blank paper, in which case the tickets may be disbursed by a vending 15 machine having a quick acting feed, or they may be torn from the strip by hand. In either case the tension device will prevent the strip from being torn or otherwise damaged as it is withdrawn from the roll.

20. What is claimed as new is:—

1. A device of the character described comprising a frame, a web-feeding roll journaled thereon, intermittently actuated means for advancing said web and normally holding 25 it taut, a guide tube in alinement with the axis of the feed-roll through which said web advances, and reciprocating means loosely mounted on the feed-roll shaft engaging the free length of said web, when 30 said advancing means is inactive, to urge said web forwardly beyond the axis of said feed-roll, said reciprocating means being controlled by said intermittently advancing means.

35. 2. In a tension device comprising a frame, a strip-feeding drum mounted thereon and means for intermittently advancing said strip, the combination of a guide-tube through which said strip advances, alining 40 with the axis of said drum, a journal way, a roller guided in said journal-way, said roller traversing said way in one direction to unwind a portion of said strip and thereby rotate said drum, means for holding said

unwound portion bowed with respect to said 45 guide and the axis of said drum, said advancing means causing said roller to traverse said way in the opposite direction to draw said web taut and thereby replace the rotation of said drum, and means carried 50 by the drum shaft for actuating said roller when in its last-named position.

3. A device of the kind described comprising in combination a frame, a web-feeding drum mounted thereon, intermittent 55 advancing means engaging said web, a journal way, reciprocating means adjacent said feed roll traversing said journal-way and causing a portion of said web to move therewith, said reciprocating means moving in 60 one direction to rotate said drum but replacing said rotation when said advancing means is active, and means loosely mounted on the feed roll shaft, controlled by said advancing means, for actuating said reciprocating means.

4. A device of the kind described comprising a frame, a web-feeding drum revolvably mounted thereon, a guide tube traversed by the web, a spring-pressed reciprocating arm loosely mounted on the shaft of the feed-roll, a journal way, said tube alining with the axis of said feed roll and said journal-way being concentric therewith, a tension roller carried at the free end of said 70 arm and traversing said journal-way, said roller when at one end of said way bowing said web with respect to said tube and the shaft of said drum, and means for drawing said web taut, thereby urging said tension 75 roller to the other end of said way.

In testimony whereof I have hereunto set my hand in presence of two subscribing witnesses.

OSCAR OEHRING.
